APPARATUS FOR STERILIZATION OF FLOUR OR THE LIKE

Kurt H. Conley, Bridgeport, Conn., assignor to
The Safety Car Heating and Lighting Company,
Inc., a corporation of Delaware

Application September 17, 1940, Serial No. 357,086

8 Claims. (Cl. 99—250)

This invention relates to apparatus for sterilization or deinfestation of milled produce such as flour, cereals, etc., and more particularly to a machine for destroying insect life in any of its stages which may infest the produce.

One of the objects of this invention is to provide an inexpensive flour sterilizing machine, which is capable of rapidly treating large quantities of flour, to destroy such insect life as may be present therein. Another object is to provide a machine of the above nature which is sturdy and simple in construction and reliable and efficient in operation. Another object is to provide a machine of the above nature which may be easily installed and operated, and the various parts of which are readily accessible for replacement or repair. Other objects will be in part apparent and in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, wherein I have shown one embodiment of my invention,

Figure 1 is a front elevation of my machine, certain portions being shown in section and others being broken away;

Figure 2 is a reduced top plan view of the machine shown in Figure 1;

Figure 3 is an enlarged fragmentary vertical section of the insect destroying instrumentalities of my machine;

Figure 4 is a horizontal section taken along the line 4—4 of Figure 1, a portion thereof being broken away;

Figure 5 is a fragmentary vertical section showing a portion of the lubricating system in my machine;

Figure 6 is a vertical section taken along the line 6—6 of Figure 5;

Figure 7 is an enlarged fragmentary vertical section of a portion of the rotor;

Figure 8 is a perspective view of the spindle housing supporting spring; and,

Figure 9 is a horizontal section taken along the line 9—9 of Figure 1.

Similar reference characters refer to similar parts throughout the various views of the drawings.

The disclosure of the present application relates to the subject matter of the following applications of Franklin S. Smith, each entitled "Method and apparatus for sterilizing flour and

the like": Serial No. 321,680, filed March 1, 1940; Serial No. 296,543, filed September 26, 1939; Serial No. 296,544, filed September 26, 1939; and, Serial No. 345,715, filed July 16, 1940. Subject matter common to the present application and any Smith application is covered in the latter.

Referring now to Figure 1, my machine includes a base generally indicated at 10, which is secured to a casing generally indicated at 11, the two being fastened together as by bolts 12, and supported by a suitable number of legs 13. A motor 14 is mounted on base 10, and through a belt and pulley drive generally indicated at 15, operates a spindle rotatably mounted in a spindle housing 16. Spindle housing 16 is in turn flexibly mounted in casing 11 in a manner specifically described below. The upper end of the spindle has secured thereto a rotor generally indicated at 17, which directly receives the flour which flows into the upper part of casing 11. The flour is forced by centrifugal force through rotor 17 and falls through channels (described below) in casing 11 into such conduit or hopper (not shown) as may be desirably attached thereto. During the passage of the flour through rotor 17, such insect life as may be present is destroyed in a manner which will be more particularly described hereinafter, so that the flour passing down through casing 11 is free of infestation.

As shown in Figure 1, motor 14 has a mounting flange 14a which is bolted to a mounting plate 18 (Figure 2) having formed thereon bosses 19, 20, 21 and 22. Through these bosses, the latter three of which are slotted for a purpose to be described, extend mounting studs 23, boss 21 also having threaded through one end thereof a set screw 24. As shown in Figure 1, studs 23 are threaded into the top 25 of base 10. Base 10 also includes a bottom 26 spaced sufficiently below top 25 to form a transmission chamber 25a or the like into which extends the lower end 27 of the armature shaft of motor 14. A pulley 28 is attached in any desirable manner to end 27 of the armature shaft.

To provide access to the interior of chamber 25a, an opening 30 is formed therein, provided with a trap door 29 hinged to bottom 26, the trap door being held closed by suitable wing nuts and swing bolts generally indicated at 31. Trap door 29 also has an opening 32 across which is stretched a piece 33 of material, such as flannel, which acts as a breather for transmission chamber 25a.

Still referring to Figure 1, base 10 has a

flange 34 to which is bolted by bolts 12 a flange 35 formed on casing 11. Flange 35 frames the opening into an interior portion of casing 11, which forms a continuation of transmission chamber 25a.

Casing 11 includes a horizontal partition or base portion 36 which has bolted thereto a bracket generally indicated at 37. Bracket 37 includes a U-shaped base 38 which surrounds an opening 39 normally closed by a hemispherical shell 40 having a drainage plug 41 in the bottom thereof. Shell 40 is bolted to the bottom of partition 36 and forms a catch basin for any oil dripping into the transmission chamber. Bracket 37 also includes a pair of upwardly extending diverging arms, such as arm 42, which has a relatively heavy boss 43 formed at the outer end thereof. Cast with arm 42 is another boss 44 through which extends a set screw and lock nut 45, the former of which is adjustable to bear against the top of partition 36 and accordingly support arm 42. The other arm of bracket 37 is similar to arm 42, but is spaced therefrom to provide therewith a pair of spaced supports to which the free ends of a U-shaped spring 46 (see also Figure 8) are attached, as by bolts, such as bolt 47 (Figure 1) which extends through boss 43. Bolt 47 is threaded to a clamp nut 48 which when taken up securely clamps one end of spring 46 against boss 43. The closed or circular end 49 of spring 46 has bolted thereto a flange 50, which extends at right angles from a semi-circular wall 51, both of which form preferably integral parts of a pulley housing generally indicated at 52. Pulley housing 52 is bolted to the bottom of spindle housing 16, and forms therewith a unitary structure resiliently mounted on a support 180 (Figure 3) as will be more fully described below.

In the upper portion of pulley housing 52 (Figure 5) is formed a transverse web 54 having a centrally disposed boss 55 formed therewith through which extends a bore 56. An annular flange 57 forms the top of pulley housing 52, and to this flange spindle housing 16 is bolted, as by studs and nuts 58, a gasket preferably being clamped therebetween.

As shown in Figure 5, the lower end of spindle housing 16 has an internal flange 59 formed therein to provide a stop against which a felt washer 60 is pressed by a shoulder 61 of a bearing housing generally indicated at 62. Bearing housing 62 includes a cylindrical portion 63 within which the outer race of a ball bearing 64 is secured by a bearing retaining disc 65 bolted against a flange 66 on the lower portion of bearing housing 62 by studs 67 threaded into the lower portion of spindle housing 16. It should be noted that portion 63 of bearing housing 62 is disposed within the bottom 16a of spindle housing 16 and is slightly reduced as at 69 to provide a small channel for the flow of lubricant to a port 70 formed in the bearing housing, and communicating with bearing 64. Thus at least a portion of any oil gathering in the bottom of spindle housing 16 flows through and is filtered by felt washer 60 into channel 69 through port 70 to bearing 64. Any other oil gathering in the bottom of the spindle housing may flow through a hole 71 formed in the spindle housing into a chamber 72 formed by web 54 of pulley housing 52.

As shown in Figure 3, the upper end of spindle housing 16 is provided with a journal 73 in which a bushing 74 is held as by a force fit, for ex-

ample. It will now appear that bushing 74 and ball bearing 64 (Figure 5) comprise journals for a spindle generally indicated at 75. Thus spindle 75 includes a reduced portion 76 about which is forced the inner race of ball bearing 64, the bottom end 77 of the spindle being further slightly reduced and provided with a key 78 so as to receive a pulley 79 which is held thereon by suitable lock nuts and washers generally indicated at 80. Disposed about end 77 of spindle 75 and clamped between the inner race of ball bearing 64 and the hub of pulley 79 is a pump impeller generally indicated at 81, which is generally cup-shaped and provided with a flange 82 formed and disposed to rotate within an annular channel 83 formed in pulley housing web 54. The top of channel 83 is substantially closed by ring or washer 84 screwed to web 54, the inner periphery of this plate clearing the outer periphery of impeller 81 by a suitable amount.

A hole 85 formed in pulley housing web 54 communicates with channel 83 and also with a vertically extending hole 86, also formed in the pulley housing. Hole 86 in turn communicates or is connected to a hole 87 formed in the lower portion of spindle housing 16 and the upper end of this latter hole receives the bottom end of a pipe 88. Pipe 88 extends upwardly within spindle housing 16, and its upper end is connected to a fitting 89 threaded into spindle housing 16 within a cylindrical drilling 94 capped by an oil hole cover 94a. Oil hole or drilling 94 communicates as by a port 91 with an annular groove 92 formed in the upper end of the spindle housing and adjacent the central portion of bushing 74, which portion has one or more holes 74a formed therein through which oil can flow to lubricate the spindle. Such oil as flows through holes 91 and 74a and does not flow upwardly and downwardly of bushing 74, flows through another hole 93 formed in the upper end of spindle housing 16 and into a channel 93a from which it may drain, to the interior of spindle housing 16 to collect in the bottom thereof, see Figure 5, and pass either through felt washer 60 or through hole 71, as hereinbefore described.

It will thus appear that upon rotation of spindle 75, and accordingly impeller 81, oil is forced by impeller flange 82 through holes 85, 86 and 87 into pipe 88, and accordingly into oil hole 94 (Figure 3). From here the oil flows through holes 74a in bushing 74 and then drains into the bottom of the spindle housing to lubricate ball bearing 64 (Figure 5). Preferably I provide a drain pipe 96 which communicates with hole 85 in pulley housing web 54 to drain chamber 72 when desired.

With reference to Figure 3, it may be seen that the upper end 98 of spindle 75 is tapered and has secured thereto a key 99, the taper corresponding with a tapered opening 100 in rotor head 17a. This tapered opening 100 also has a keyway which receives key 99 when the rotor is assembled to spindle 75. The upper end of spindle 75 (Figure 3), i. e. the end extending upwardly of taper 98 (Figure 1), is threaded to receive an interiorly threaded nut 101 provided with a flange 102 at its bottom. When nut 101 is threaded on the end of spindle 75, flange 102 presses against the top of rotor head 17a to hold the rotor on the spindle. The upper end of rotor end 17a is exteriorly threaded to receive a generally frusto-conical spreader 103 provided with a lip 104 adapted to fit on top of nut flange 102. After

nut 102 and spreader 103 are assembled, the spreader is staked as at 105 to connect it permanently to the top of rotor head 11a. It may now be seen that when nut 101 is unthreaded from the top of spindle 75, its flange 102 pulls upwardly against spreader lip 104 and accordingly lifts rotor 17 off the top of the spindle.

Inasmuch as the oil which lubricates spindle 75 (Figures 3 and 5) must be completely segregated from the flour which is treated by rotor 17, I provide adjacent the top of spindle housing 16 a running seal generally indicated at 106 (Figure 3). Seal 106 includes a generally cylindrical seal body 107, the upper portion of which is annularly grooved as at 108 to receive a seal 109 secured in the groove as by cement 110. The lower portion of seal body 107 has a flange 111 against the bottom of which is clamped a flexible diaphragm 112 by a ring 113, screws 114 extending through the ring and diaphragm and being threaded into flange 111 to hold the several parts together. Preferably screws 114 are cemented in their holes by oil-proof cement.

The outer portion of diaphragm 112 of seal 106 is clamped against an annular extension 115 of spindle housing 16 by a diaphragm ring 116, the ring being held on the extension as by screws 117 or the like, which extend through the ring and diaphragm and are threaded into the extension. When oil seal 106 is in its assembled operative position, seal body 107 surrounds the upper end of journal 73 and is movable relative thereto by reason of the flexibility of diaphragm 112. Thus seal 106 is adapted to be biased upwardly, as will be explained, so that the upper portion of seal 109 may be pressed against a seal ring 118 secured to the bottom of rotor head 11a, and having a close sliding fit with portion 75a of spindle 75. Preferably seal ring 118 is formed of hard steel whereas seal 109 is formed of graphite, thereby providing an efficient running seal to preclude flow of oil from inside spindle housing 16 into casing 11. Thus the oil is efficiently and completely segregated from the flour treated by rotor 17, but is free to flow within seal body 107 about the upper end of journal 73 and a portion of spindle 75 extending thereabove as the seal body is slightly spaced from the journal and spindle.

As noted above, seal body 106, and accordingly seal 109, are preferably biased upwardly against seal ring 118 and to this end, as shown in Figure 3, I provide a suitable number of seal plungers 119 slidably mounted in holes provided therefor in the upper part of spindle housing 16. Each plunger 119 has a cap 120 pressed against the bottom of ring 113 by a spring 121 intervening the cap and the bottom of channel 94. Thus, an oil-tight seal between spindle 75 and rotor 17 precludes escape of the oil from its proper channels of flow. It might be added that lubrication of the running seal is obtained not only from graphite ring 109, but also from oil vapor issuing from the oil forced between bushing 74 and spindle 75 adjacent the top of the bushing.

To assure proper operation of the lubricating system hereinabove described, it is necessary to have a sufficient supply of oil in pulley housing chamber 72 (Figure 5). Preferably this chamber is maintained about half full of oil, and as there is some loss of oil from possible leakage and evaporation, it is necessary to have a supply available to maintain the proper level. To this end I provide an oil reservoir generally in-

dicated at 122 having an outlet 125 which communicates with chamber 72, and an inlet which communicates with an oil filler generally indicated at 123.

Reservoir 122 includes a chamber 124 (Figure 6), preferably U-shaped and of sufficient capacity for the purpose intended. Outlet 125 (Figure 5) of reservoir 122 communicates with a channel 126 formed in pulley housing 52 when reservoir 122 is bolted thereto as by bolts 127, a gasket 128 preferably being clamped between the reservoir and pulley housing to prevent oil leakage. As shown in Figure 6, reservoir chamber 124 has an upper extension 129 having an opening 130 formed therein which receives the nozzle 131 of an oil conduit generally indicated at 132 (Figure 5). Adjacent the upper end of nozzle 131 the conduit is provided with oppositely extending wings or flanges 133 and 134, which substantially cover reservoir opening 130 without resting against the top of chamber extension 129, so as to permit free motion of the spindle unit with the attached reservoir 122 and the passage of air into the reservoir for a purpose described below.

Oil conduit 132 is preferably slightly inclined from the horizontal to facilitate flow of oil therethrough and extends from a preferably vertical plate or flange 135, by which conduit 132 and filler 123 are attached to a portion 11a of casing 11. The channel 132a of oil conduit 132 extends to the left through plate 135, as viewed in Figure 5, to terminate in a chamber 137 formed in the base 138 of oil filler 123. One side of base 138 may be drilled and plugged as at 139 to permit access to chamber 137.

The top of filler base 138 has a flange 140, providing a seat for a gasket 141 on which a cylindrical filler glass 142 rests. Filler 123 includes a flanged cap 143 which, with a gasket 144, rests on the top of filler glass 142. Cap 143 has bosses 145 formed thereon through which extend studs 146, the bottom ends of which, when threaded into filler base 138, securely clamp and seal filler glass 142 between the filler cap and base. Filler cap 143 also includes a drilled and interiorly threaded extension 147 into which a plug generally indicated at 148 is threaded. The lower end 149 of plug 148 is reduced and extends through a gland 150 to preclude passage of air through filler cap extension 147. Also, I preferably provide a gasket 151 in the knurled head 148a of plug 148 which bears against the top of filler cap extension 147 when plug 148 is screwed down thereon further to seal the filler.

The bottom of plug end 149 abuts the top of a plunger 152 slidably disposed within the upper end 153 of a valve generally indicated at 154. A portion 155 of valve 154 is threaded into filler bottom 138 and preferably sealed therein with oil-proof cement. Extending downwardly from threaded portion 155 of the valve is a cage 156 within which a ball 157 is disposed. This ball rests on the upper end of a spring 158 disposed within a hole 159 bored in filler base 138. Plunger 152 and valve 154 are so proportioned with respect to ball 157 and spring 158 that when the several parts are in the position shown, the ball and cage 156 lie within chamber 137, the plunger forcing the ball against the bias of the spring downwardly from the seat 154a of valve 154, to permit flow of oil from filler glass 142 to conduit passage 132a. When, for purposes of replenishing the supply of oil with-

in filler 123, plug 148 is unscrewed, spring 158 forces ball 157 and accordingly plunger 152 upwardly until the ball rests against seat 154a, closing chamber 137.

It may now be seen that when filler 123 is full of oil and ball 157 is spaced from valve seat 154a, oil can flow from glass 142 through valve 154 and chamber 137 into conduit passage 132a. Thence the oil flows through conduit nozzle 131 into reservoir 122. As shown in Figure 6, conduit nozzle 131 is inclined from the vertical so that one side 131a of the nozzle opening is higher than its other side 131b. The oil level in reservoir 122 determines whether or not oil can flow from filler 123 (Figure 5) into reservoir 122 (Figure 6). If the oil level is above side 131a of nozzle 131, oil cannot flow from the nozzle into the reservoir as to do so under the stated conditions would create a vacuum within filler glass 142 (Figure 5). If, however, the oil level drops below side 131a (Figure 6) of conduit nozzle 131, the air which can enter reservoir 122 through its opening 130 beneath conduit wings 133 and 134, bubbles up through conduit nozzle 131 and conduit passage 132a into filler glass 142, to prevent formation of a vacuum therein. Thus as air flows into glass 142, oil can flow therefrom into reservoir 122. The inclination of filler nozzle 131, as described above, facilitates the flow of oil downwardly and the bubbling of air upwardly therethrough, and tends to prevent the formation of an oil film across the opening of nozzle 131 which might occur were the nozzle vertical. Such a film might prevent necessary flow of oil.

From the above, it may be seen that filler 123, reservoir 122 and impeller pump 81 (Figure 5) supply an ample quantity of oil to the various bearing surfaces of spindle 75, its housing 16 and to ball bearing 64. Through the various channels and pipes in spindle housing 16, all as described above, bushing 74 (Figure 3) at the upper end of the spindle is amply supplied with oil, while ball bearing 64 (Figure 5) is amply lubricated by oil which runs down spindle 75 over a deflector collar 75b and collects in the bottom of the spindle housing over felt washer 60. Furthermore, the oil level in chamber 72 in pulley housing 52 is maintained at the proper level through the described operation of reservoir 122 and filler 123.

As heretofore described, bosses 20, 21 and 22 (Figure 2), of motor mounting plate 18, are provided with elongated slots. These slots permit pivotal movement of motor 14 about its fastening stud 23 in boss 19 when the several studs are loosened for the purpose of displacing the motor axis relative to the axis of spindle housing 16 as desired, to adjust the tautness of belts 160 of belt and pulley drive 15. Such adjustment is maintained by adjustment of set screw 24, which extends into the slot in boss 21 and bears against motor stud 23. It might also be noted at this point that by reason of the spaced parallel relationship of the axes of motor 14 and spindle housing 16, access to each may readily be had as required, without necessitating any great amount of disassembly of the machine as a whole. Through the provision of trap door 29 (Figure 1) the various parts within transmission chamber 25a in base 10 are easily accessible. Also in this connection, as base 10 is secured to casing 11 by bolts 12, these two parts are readily separable as may be desired.

With reference to Figure 1, it will be seen that casing 11 includes a generally funnel-shaped

portion 161 which narrows at its lower end to a flanged opening 162 connectable as desired to a bin or conduit (not shown). The top of funnel or casing portion 161 is closed by a cover 163 which may be secured in closed position by suitable swing bolts and wing nuts 166 (Figure 2). Cover 163 includes a pair of bosses 164 and 165; and an elongated shaft 167 (see also Figure 1) extends through boss 164 wherein it is securely fastened to prevent relative movement therebetween. This shaft extends downwardly from cover 163 outside of casing 11, and through a bracket 168 bolted to top 25 of base 10. As shown in Figure 1, the lower end of shaft 167 extends below the bottom of base 10 and rests on one end of a leaf spring 169, the other end of which is clamped to casing flange 35 by bolt 12. Spring 169 biases shaft 167 and accordingly cover 163 upwardly to assist the operator in raising the cover.

The lower end of shaft 167 has an elongated key 170 secured therein and this key is slidable within a slot (not shown) formed in bracket 168. Through the provision of this key and slot, pivotal or swinging movement of cover 163 relative to rotor 17 is impossible until the key clears the slot. When the shaft and cover have been raised high enough for the key to clear its slot, the cover may be swung over the top of spindle nut 101. To guide and assist in holding cover 163 (Figure 2) in its proper position on top of casing section 161, another shaft 171 is secured in boss 165, and when the cover is in closed position, this shaft extends through a hole in a boss (not shown) on casing section 161. Shaft 171, however, is shorter than shaft 167, and accordingly no provision for its reception in base 10 is necessary. It should be noted that when cover 163 is raised to its upper position, the bottom of key 170 may ride on the top of bracket 168 as the cover is swung to prevent it from dropping.

Casing section 161 has preferably integrally formed therewith an inner partition 172 (Figures 1 and 9) which divides the interior of the casing 45 into two channels 173 and 174. The inner and outer walls of each of these channels are respectively formed by walls 175 and 176 of casing section 161, wall 175 being substantially cylindrical in shape and terminating in a mounting flange 50 177 at its upper end (see also Figure 3). The left-hand side of casing section 161 (Figure 1) is inclined from the vertical, whereas the right-hand side thereof is preferably substantially vertical so that the casing section narrows from top 55 to bottom. Inasmuch as the channels 173 and 174 must follow around the inner wall 175 while progressing downward toward the common opening 162, these channels are helical in shape; also progressive cross sections downwardly of 60 channels 173 and 174 do not materially vary in shape at their bottoms but both increase in depth until they merge at opening 162 at which point they occupy the entire height of casing section 161. I have found that by so arranging channels 65 173 and 174, the flow of the treated flour from the treatment zone at the top of casing 11 is considerably expedited.

As noted above, inner wall 175 of casing section 161 (Figure 3) terminates in mounting flange 70 177 for the upper end of spindle housing 16. The upper end of spindle housing 16 has an outwardly extending flange 178 formed thereon through which extend a number of bolts 179 which are threaded into a disc 180 underlying housing flange 178. Disc 180 is attached as by

vulcanizing to a rubber ring 181, in turn vulcanized to a mounting ring 182. The diameter of ring 182 exceeds that of rubber ring 181 and is secured to the top of casing wall flange 177 as by bolts 183. Thus the top of spindle housing 16 is flexibly or resiliently connected by way of rubber ring 181 to flange 177 of casing wall 175 so that a limited amount of relative movement is possible therebetween. During the operation of my machine, spindle 75 may rotate at a rate on the order of 4000 R. P. M., and if, for any reason, the flour being treated by rotor 17 should clog in one portion thereof and unbalance the rotor, the center of gravity of the rotor would shift relative to its center of rotation, i. e. the axis of spindle 75, and if suitable compensation were not provided for this displacement, a serious condition of vibration would result. In other words, the tendency would be for the rotating mass, i. e. rotor 17 and flour clogged therein to rotate around the center of gravity with the result that certain forces would be set up, causing undue pressure of the upper part of spindle 75 on bushing 74. By reason, however, of the flexible mounting provided by rubber ring 181, spindle 75 and accordingly rotor 17 can move relative to casing 11, thus permitting the rotor and shaft to rotate about any center of gravity within reasonable limits caused by the unbalanced condition of the rotor.

To limit the displacement of the center of rotation, I provide a rubber buffer ring 184 (Figure 3) which is secured in a circular slot in the upper part of spindle housing 16 within and adjacent to the inner periphery of resilient ring 182. It may now be seen that if rotor 17 becomes unbalanced and causes radial displacement of spindle 75 and accordingly spindle housing 16, this displacement will occur at the same speed as the rotation of the spindle. In other words, the center of the spindle at its top will rotate in a circle instead of in a point. By reason of the lower flexible mounting of spindle housing 16 (Figure 5) provided by U-shaped spring 46, this rotation of the center of spindle 75 at the top is made possible. Furthermore, the provision of spring 46 is a positive deterrent to rotation of spindle housing 16 relative to casing 11 so that in the event of abnormal friction between bushing 74 (Figure 3) and spindle 75, there will be no torque transmitted to the bond between rubber ring 181 and rings 180 and 182.

As pointed out hereinabove, rotor 17 (Figure 3) is secured to the top of spindle 75. The rotor includes a body generally indicated at 53 comprising a head 17a and an intermediate or side portion 17b from which a base 17c extends. The outer surface of rotor side portion 17b, which may be curved, is inclined from the horizontal plane of the top 185 of rotor base 17c and this inclination may be generally on the order of 45°. The outer surface of rotor head 17a is preferably more steeply inclined from the horizontal. Thus rotor body 53 is generally semi-pseudospherical in shape which, I have found, effects a substantially uniform distribution of the flour throughout the treating zone of the rotor.

Extending upwardly through rotor base 17c are four vertical stud bolts 186, 187, 188 (Figure 4) and 189, the former two of which, as shown in Figure 3, have bushings 190 disposed thereabout and resting on surface 185 of rotor base 17c. Stud bolts 188 and 189 (Figure 4) are preferably unbushed and different in size, bolt 188 preferably being larger than bolt 189 for a purpose

70 which will be described. These four stud bolts 186-189 are equi-angularly spaced about rotor base 17c and support proper operative position a plurality of rotor discs 191.

5 Each of discs 191 is provided with four holes through two of which bushed stud bolts 186 and 187 extend, and through the other two of which stud bolts 188 and 189 (Figure 4) extend. Of course, the latter two holes are different in size 10 so as to conform to the different sized bolts 188 and 189. Through the provision of bushings 190 (Figure 3) assembly of the several plates is facilitated and still a snug fit is effected between the plates and stud bolts. Inasmuch as bolts 188 and 189 (Figure 4) are of different size, it is possible to assemble plates 191 thereon in one position only, thus assuring that the discs will 15 always be assembled in the proper relationship and position with respect to one another so that the initial balancing of the rotor as a whole cannot subsequently be destroyed upon reassembly.

20 As is more clearly shown in Figure 7, the bottom A of each disc 191 is horizontal, whereas the top B thereof is slightly inclined from the horizontal with the result that the thickness of the plate at its outer periphery exceeds that at its inner. Also, each of these discs has a plurality of holes 192 equi-angularly spaced about its outer periphery, each adapted to receive a spacer stud 25 193. Stud 193 is preferably T-shaped in vertical cross section and accordingly has a broader head than shank. As the head of each spacer 193 extends above the plane of the top of its disc 191, the several spacers on each disc hold the disc immediately above a predetermined distance 30 therefrom. Hence, adjacent surfaces of adjacent discs define a frusto-conical gap C (Figure 7) wider at its entrance or inner end than at its outer or exit end. Preferably the entrance D of gap C is substantially widened through the provision of a bevel 191a at the upper edge of the inner periphery of each of discs 191. Thus, as is more clearly shown in Figure 3, when a plurality of plates 191 are assembled on rotor base 17c, 35 a series of spaced gaps C are provided thereby. It is through these spaces C that the flour flows by reason of the centrifugal force generated upon rotation of rotor disc 17. As the flour flows through these gaps, any insect therein is destroyed through the action of the disc surfaces squeezing the insect or catching it and holding it until it is substantially disintegrated through abrasion by the flour flowing thereby. It should be noted that when reference is made to insects, 40 all stages (eggs, larvae, pupae and adults) are contemplated.

45 The topmost plate 191b (Figure 3) underlies a clamp plate 194, and fits about bushings 190 (Figure 4) and stud bolts 188 and 189, being held in position thereon by nuts 195 threaded on the upper ends of the several stud bolts.

50 The inner edge 194a of clamp plate 194 is of lesser diameter than that of the inner edges of plate 191, and thus forms a mounting surface for a rotor collar generally indicated at 197. Collar 197 is secured to clamp plate 194 as by stake screws 198, the collar being provided with arcuate cut-outs 199 (Figure 4) within which nuts 195 lie when the collar and plate 194 are secured together. As the collar's thickness is greater than that of nuts 195, the collar acts as a fairing for the nuts, thus precluding excessive noise and objectionable turbulence within casing cover 163. Furthermore, the service of collar 197 as a fairing for the nuts reduces the wind resistance

which the nuts would offer if completely exposed.

The inner edge 197a of collar 197 slopes downwardly and outwardly with respect to the collar's axis, and the upper end 197b of this edge lies substantially above the lower edge of a throat 200 preferably formed integrally with and extending downwardly from casing cover 163. This edge 197b is sufficiently spaced from the outer surface of throat 200 so as to provide ample clearance to accommodate lateral displacement of the axis of rotation of rotor 17, by reason of its becoming unbalanced.

It should also be noted that the lower edge 200a of throat 200 is beveled and closer to the surface of rotor head 17a than is the upper edge 200b thereof. Thus the space between rotor head 17a and the inner surface of throat 200 is larger at the top than at the bottom, where the centrifugal force begins to increase rapidly due to the flaring out of rotor portion 17b.

A throat extension 201 (Figure 1), concentric with throat 200 and of the same diameter, is secured to bosses 202 on the top of casing cover 163 as by screws and wing nuts 203, and it is within this extension 201 that spreader 103 whirls. The top of spreader 103 is preferably inclined or beveled as at 103a so as to be more nearly horizontal than rotor head 17a. Thus the spreader has the double effect of regulating the feed of flour through throat extension 201 and throat 200, and of uniformly distributing the flour within rotor 17. It should also be noted that as the space between spreader 103 and throat extension 201 is less than that between rotor portion 17b and the bottom edge 200a of throat 200, the constriction afforded by the spreader meters the flour flowing into throat 200 so as to prevent any possibility of the throat's becoming choked at a point where the rotor head exerts relatively little centrifugal force. In other words, the flow capacity adjacent spreader 103 is less than that adjacent the lower edge of throat 200.

The bottom edge 200a of throat 200, it will be noted, is adjacent the upper end of rotor side portion 17b; hence there is no obstruction to the flow of flour outwardly of rotor body 53 in the treatment zone of the rotor.

Spreader 103 also has a further function, in addition to those heretofore described. When a stoppage occurs in rotor 17 by reason of flour or some foreign particle clogging between rotor plates 191 and the center of gravity of the rotor accordingly shifts laterally, the upper end of spindle 75 rotates in a circle instead of a point, as described. The effect of this is to cause spreader 103 to travel in a circular path inside of throat extension 201. Hence at any instant, under such circumstances, there is one point on the periphery of spreader 103 which is nearer to throat extension 201 than any other point on the spreader, and that former point lies above the center of mass of the stoppage in rotor plates 191 and in the vertical plane passing therethrough. Thus the flow of flour into the rotor would be substantially diminished at the clogged portion thereof.

From the above description, it will appear that as flour flows into rotor 17 past spreader 103 and through throat 200, its feed is regulated and it is uniformly distributed to the interior of the rotor where the centrifugal force generated thereby can act on it. This force throws the flour radially of the rotor, causing it to flow uniformly through the gaps between plates 191, and as the flour flows through these gaps, such insects as may be present therein are destroyed. As the

flour is thrown out of the gaps between the plates, it impinges against the sides of casing cover 163, and flows downwardly through the casing through channels 173 and 174 therein to casing opening 162. It will also appear that by reason of the flexible mountings for spindle housing 16 provided through rubber ring 181 and spring 46, such clogging as may occur in rotor 17 causing lateral displacement thereof is accommodated through the flexibility of these mountings. Still further, by reason of the parallel, spaced relationship of motor 14 and casing 11, and the construction thereof as separate units, such vibration as is generated through the rotation of rotor 17 is not transmitted directly to the motor, and also by reason of the separation of the two, each is separately accessible for such repairs or replacement of parts as may become necessary.

Accordingly, I have provided a machine for destroying insects in flour which attains the several objects hereinabove set forth in a thoroughly practical and efficient manner.

As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In apparatus for destroying insects in a milled product, in combination, means forming a casing construction having an inlet opening at the top thereof, a rotor rotatably mounted in said casing and including a body portion generally semi-pseudospherical in shape and having an imperforate surface, and an outwardly extending annular flange mounted upon the top of said rotor and forming a constriction in said inlet opening, and means for rotating said rotor.

2. In apparatus for destroying insects in a milled product, in combination, a casing, a rotor mounted in said casing and including a body portion having a base extending therefrom, a plurality of plates mounted on said base in spaced relation to form annular gaps therebetween, a plurality of securing studs extending through said plates to assist in securing said plates to said base, a collar extending around each of said studs and through said plates, a stud of smaller diameter than said plurality of studs and extending through said plates to assist in securing said plates to said base, and means for rotating said rotor.

3. In apparatus for destroying insect life, in combination, a base, a spindle housing mounted on said base, a spindle rotatably mounted in said housing, an apertured rotor secured to said spindle and rotatable therewith for destroying insects, casing means secured to said base and enclosing said housing and rotor, said casing means including a cover, a shaft connected to said cover and extending downwardly therefrom into said base, said shaft being raisable to lift said cover, key and slot means associated with said shaft and base to prevent rotation of said shaft and cover while said shaft is in its lower position, said shaft being rotatable when raised to swing said cover and expose said rotor, and spring means for biasing said shaft upwardly.

4. In apparatus for destroying insect life, in combination, a base, a spindle housing mounted on said base, a spindle rotatably mounted in said housing, an apertured rotor secured to said spindle and rotatable therewith for destroying insect

life in flour flowing therethrough, casing means secured to said base and enclosing said housing and rotor, said casing means including a cover, a shaft connected to said cover and extending downwardly therefrom into said base, said shaft being raisable to lift said cover, key and slot means associated with said shaft and base to prevent rotation of said shaft and cover while said shaft is in its lower position, said shaft being rotatable when raised to swing said cover and expose said rotor, spring means for biasing said shaft upwardly, and means for precluding pivotal movement of said shaft until said shaft is elevated a predetermined distance.

5. In apparatus for destroying insect life, in combination, a base, a housing mounted on said base, a spindle rotatably mounted in said housing, an apertured rotor mounted on said spindle for rotation therewith for destroying insect life in a product flowing therethrough, a casing secured to said base and enclosing said housing and rotor, and means forming a pair of downwardly extending channels within said casing, the upper ends of said channels being adjacent the bottom of said rotor and adapted to receive the product passing therethrough, at least one of said channels being generally spiral throughout a substantial portion of its extent.

6. In apparatus for destroying insect life, in combination, a base, a bracket secured to said base, a spring secured to said bracket, a spindle housing secured to said spring whereby said housing is resiliently mounted on said base, a spindle rotatably mounted in said housing, means on said spindle and rotatable therewith for destroying insect life, a casing secured to said base and enclosing said housing and spindle, and means forming a flexible connection between said housing and said casing, said flexible connection and said spring being adapted to accommodate lateral displacement of the axis of rotation of said spindle.

7. In apparatus for destroying insect life in a milled produce wherein the produce is forced with sufficient velocity against treating surfaces to destroy the insect life by abrasion and impact thereof against such surfaces, the combination of, a

- base constituting the main support of the apparatus, a high speed motor mounted on said base, a driving member secured to said motor to be driven thereby, a casing rigidly connected to 5 said base, a spindle housing flexibly connected at its upper end to said casing and its lower end to said base, a spindle rotatably mounted in said housing and having its lower end extending into said base, a driven member attached to the lower end of said spindle, driving means connecting said driving and driven members whereby operation of said motor rotates said spindle at high speed, a rotor mounted on the upper end of said spindle within said casing and having treatment surfaces 10 against which any insect life in the produce is abraded and impacted to effect the destruction thereof during rotation of the rotor, and a cover plate secured to said casing and enclosing said rotor.
- 15 8. In apparatus for effecting the destruction of all insect life in a flowable product composed of individual solid parts, the combination of, a rotary treating device, confining means associated with said device and forming a treating space 20 confined to the dimensions of said device and having an inlet forming an unrestricted passageway to allow a substantially even stream of said product to flow to said treating space, the smallest dimension of said treating space being larger than 25 the maximum dimension of the individual parts of said product, means for flexibly mounting said rotary treating device within said confining means, means to feed said product to said inlet so that it may flow through said treating space, 30 and means to rotate said treating device at a high speed to provide a life destroying engagement between every individual particle of insect life and said treating device during passage of said product through said treating space, said apparatus including a product outlet one section of 35 which extends substantially around said treating device so that the product may fall away from said treating device and another section substantially helical in shape and extending away from 40 said treating device.
- 45

KURT H. CONLEY.
